DESIGN FOR A TOBACCO PIPE

Arthur Koenigsamen, Jamaica, N. Y., assignor to
Henry Leonard & Thomas, Inc., Ozone Park,
N. Y., a corporation of New York

Application September 12, 1941, Serial No. 103,323

Term of patent 7 years

To all whom it may concern:

Be it known that I, Arthur Koenigsamen, a citizen of the United States and a resident of Briarwood, Jamaica, in the county of Queens, and State of New York, have invented a new, original, and ornamental Design for a Tobacco Pipe, of which the following is a specification, reference being had to the accompanying drawing forming a part thereof, wherein:

Fig. 1 is a plan view of a tobacco pipe, showing my new design;

Fig. 2 is a side elevational view thereof; and
Fig. 3 is an end elevational view thereof.

The dominant feature of my design resides in those portions shown in full lines.

I claim:

The ornamental design for a tobacco pipe, substantially as shown and described.

ARTHUR KOENIGSAMEN.
